ABSTRACT OF THE DISCLOSURE

The application discloses an improvement in a manually actuatable clothes washing implement, comprising a hand operated plunger rod fixedly connected to a bulbous, elastically deformable washer head. This head has an upper portion of conical cross-section connected to the rod, and a lower portion at which a turbulizing and suction action is exerted on the clothing and water in which they are immersed.

The lower portion of the head has externally ribbed bottom openings and unribbed side openings for the above mentioned compound action; and the natural stability and strength of the upper conical head portion are augmented by an annular, outwardly projecting and thickened rim or bead formation in the annular zone where the two portions merge.

The present invention relates to an improved, manually operated device of a very compact and inexpensive nature for the washing of clothing. More particularly, the operation of the device involves a plunger or dasher action of a novel washer head on a limited charge of clothes in a bucket or like small container of soapy or detergent liquid. Thus the device is used to particular advantage in a camp or similar locality remote from power conveniences, or when the quantity of garments to be washed does not warrant the use of a conventional power operated machine.

It is an object of the invention to provide a manually operated, plunger type washing device of this character which is capable of thoroughly, quickly and with little exertion washing many different (though usually small) articles of everyday clothing or other fabrics, such as towels, diapers, handkerchiefs, socks and the like. The device is in the form of a hollow washer head of elastically deformable material; and provision is made for the attachment to one axial end of such head, of an appropriate operating rod or handle, by which a vertical and axial, back and forth action is exerted on clothing, as immersed in washing liquid in a relatively small size container.

The construction of the head is such as to set up, following an initial purging of air from its interior through certain flushing ports, a vacuum and positive pressure responsive flow and counterflow of the cleansing liquid through these and other ports, and in opposite directions through the interstices of the fabrics, as the interior of the head is alternately pressurized and de-pressurized.

More specifically, the hollow washer head of the improved device is of a rounded and bulbous outline which is symmetric about its upright axis, being provided on a transverse wall thereof remote from the operating rod with a considerable number of liquid inflow and outflow openings or ports, through which the cleaning solution flows as the device is operated in vertical reciprocation.

Further in accordance with the invention, the edge of the openings or ports referred to is preferably bounded by an annular bead or rim of material integrally projecting outwardly of the wall in question. These rims or beads act as external gaskets to insure a better liquid suction action through the clothing, and not a dissipation of that action along the outer surface of the apertured

2

head wall; and they afford a gripping effect on the clothing simulating that exerted by the tentacle of an octopus.

Still further in accordance with the invention, the head is provided, in an annular side zone surrounding the wall 5 area of the beaded or rimmed openings referred to, with a series of circumferentially spaced air purging and liquid flushing openings, which are specially shaped to extend laterally outwardly and to some extent around the side wall of the head and toward its operating plunger rod. The last named openings make it possible to purge the 10 interior of the washer head of air, save for some small residual air volume in its zone, in the first few strokes of operation of the device, after which washing continues under a reversing liquid flow and counterflow through 15 both the rimmed and flushing openings. A washing cycle of, say, three to five minutes duration suffices for the thorough cleansing of the clothing.

The foregoing as well as other objects will become 20 more apparent as this description proceeds, especially when considered in connection with the accompanying drawing illustrating the invention, wherein:

FIG. 1 is a fragmentary perspective view of the improved washing device;

FIG. 2 is an end elevational view from the bottom end 25 of one of the two elastically deformable members of the device, i.e., the cupped and ported bottom member;

FIG. 3 is an opposite end view from the top of the other or belled top component; and

FIG. 4 is a view in axial section along a line corresponding to the line 4—4 of FIG. 2, further illustrating structural details of the improved device, and indicating in solid and dot-dash line the mode of operation thereof.

The washer head 10 of the device of the invention is 30 illustrated in FIGS. 1 and 4 in the assembled relationship 35 of its two elastically deformable components 12, 14, which are molded of natural or synthetic rubber, a suitably flexible plastic composition or the like. Members 12, 14 define a relatively large volume chamber which, in the reciprocating compression and decompression of 40 head 10, insures a desiredly long duration of vacuum to control the inflow and outflow of air and water in the priming and washing phases of the operating cycle of the device, as will be described.

The uppermost head member 12 is circularly shaped 45 in a belled outline at an annular, generally conical wall 15 of rather steep slope. This prevents the clothing from hanging up on the top of head 10 in the washing operation. The apex of wall 15 is axially thickened to provide a boss 16, which is provided with an internal helical thread 17 tightly receiving a correspondingly threaded 50 end of a wooden dowel-like operating rod or handle 18. The latter is of a length, say, of about 21"—24".

Upper bell member 12 is integrally molded to provide 55 an annular series of internal ribs 20, which afford a desired degree of stiffening to assist the wall 15 in reflexing in FIG. 4) from an axially compressed and deformed shape suggested in dot-dash line.

It will also be noted that the interior of bell member 60 12 is quite steeply domed at 20. This space retains some volume of air within the head 10 to provide an air pocket cushioning of the downward stroke of the head throughout the washing cycle.

The second component 14 of the head 10 is molded 65 in an upwardly opening, cupped and circular outline; and the members 12, 14 have equal thickness faces at planar lower and upper extremities, respectively, thereof, at which they are bonded, adhered or otherwise associated in liquid tight connection to one another at a meeting plane 22.

70 This annular zone is of a diameter of, say, 6"—6½"; and the overall axial dimension of head 10 may be ap-

proximately 5"-5½". It is intended that the improved washing device be employed in cleansing a limited amount of clothing or other relative small fabric articles at a time in a soapy water or detergent solution. It is contemplated that a plastic or galvanized bucket, pail or waste basket, designated B, of a commonly available ten to twenty quart capacity, having a height of between 9" and 14", will be employed. FIG. 4 shows the bottom of such a bucket B, clothing C being indicated.

It is desirable that a container of not too great diameter be employed, such as would detract from a desired intensity of water surge action and occasion a loss of washing efficiency. A few uses of the device will enable the optimum load limit of clothing for a given volume or amount of one sort of washing liquid or another to be readily determined. As in any conventional washing operation, an overcharge of clothing detracts from cleaning efficiency, just as over-soaping of the solution may cause a suds-clogging condition.

The bottom cup member 14 is formed to provide an enlarged, laterally projecting annular flange 24 beneath the plane 22 at which it meets bell member 12; and beneath this flange the member 14 has an annular depending wall 25, which curves downwardly radially inwardly to merge into a transverse bottom wall portion 26.

Flange 24, in conjunction with the thickened portion of member 12 directly adjoining the same, affords a thickened medial, horizontal control zone for the head 10 which insures a relatively stable collapsing action of the head members 12, 14 on either side of this zone on a downward plunger stroke, rather than a flabby and uncontrolled effect. Flange 24 also acts as a stop to prevent the clothing being washed from simply slipping up past wall portion 26, around the sides of member 12 and onto its top, on a downward stroke of head 10.

The transverse wall portion 26 is provided with a plurality of liquid inflow and outflow openings or ports 27, which come primarily into action in the washing phase, following air purging and liquid priming. These, as best shown in FIG. 2, are of the same circular size and have a diameter of, say, one inch. They are distributed, commencing with a central such port, in a number of concentric annular series, and the openings 27 in each of these series (typically shown as two, but more or less may be employed) have equal circumferential spacing from one another.

In order to improve the effectiveness of the grip of the clothing C onto the apertured transverse wall 26, and also preserve an effective suction to draw cleansing liquid through the fabrics, undiminished by side loss of vacuum along the surface of the wall, the latter is provided with integral annular beads or ribs 28 projecting downwardly and outwardly thereof, in direct surrounding relation to the respective ports 27. They localize, and to a considerable extent seal, the engagement of the clothing C across the ports or openings during the initial liquid priming and air purging portion of the washing cycle, in which air is primarily discharged from and liquid drawn into head 10 through further flushing ports (to be described).

Head 10 also includes a number of air purging and flushing ports, openings or passages 30 of approximately cam- or pear-shaped outline, shown as six in number. These are located in equally spaced circumferential relation to one another, a bit radially outward of the outermost series of ribbed ports 27, and the shape of ports 30 makes them extend radially and upwardly into the upwardly concave wall portion 25 of head member 14 from the bottom transverse wall portion 26 of said member. Thus, whereas the ribbed liquid inflow and outflow ports or passage 27 will be engaged and in effect sealed by the clothing at the outset of washing, with little or no liquid counterflow in the priming and air purging phase of operation, the flushing ports 30 remain at least partially exposed above the clothing. Thus provision is made

for an outflow of air and an inflow of liquid to prime the interior of head 10 during the first reciprocatory stroke or so of the head. Naturally, there may be some slight fluid flow through the rimmed openings 27 in this initial action, but the non-rimmed, pear-shaped openings 30 are essentially responsible for quick air purging and liquid priming. When the plunger head bottoms out against the clothing (dot-dash line in FIG. 4) the openings 30 still are sufficiently exposed to the water above the clothing to prevent the setting up of a locked vacuum condition within head 10.

In use, with the bucket B or other container charged with an appropriate volume of soapy water or other detergent liquid and a small amount of clothing, the device 15 is grasped at handle 18 and inserted downwardly into the bucket. Head 10 contacts the clothing, and as the downward movement of the head is continued, its wall portion 26 and the clothing C are bottomed to the bucket, with the wall portion in approximately flat, horizontal 20 position as suggested in dot-dash line in FIG. 4; and upper bell member 12 of the head collapses downwardly at its originally conical wall 15 to the position also suggested in dot-dash line.

Thus, up to 80% of the air in the unit is forcibly purged 25 out through the flush ports or openings 30, the rimmed holes 27 being substantially blocked by the clothing, so that negligible air is purged therethrough, as mentioned above. There may of course be some slight blockage of the priming or flushing ports 30, but sufficient thereof 30 remains exposed for an adequate desired discharge of air.

A slight upward pull on handle 18 starts to restore upper bell section 12 to its normal position shown in solid line in FIG. 4, creating a vacuum within head 10, whereupon liquid commences to flow into and through ports 35 30. The vacuum is considerably greater than can be relieved in an instantaneous flooding of the flush ports 30 with inflow water, with the result that loose floating parts of clothing adjacent such flush ports is drawn against the latter, thus tending to an external blocking of ports 30. 40 Consequently, a condition of increased head vacuum arises, which becomes more and more effective through the bottom rimmed or beaded ports 27, and clothing directly held across the same. Now, as the upstroke of head 10 is continued to lift head 10 further from the bucket 45 bottom the combined effect of the upward pull on the handle and the resilient return spring of the head wall 15 is to maintain the vacuum created in the head. Accordingly, the clothing C continues to be vacuum-held across openings 27, 30. However, the porosity of the clothing 50 weave is such that this vacuum will not be long maintained. Hence, following release of downward holding pressure and continuance to completion of the upward stroke of head 10, soapy water or detergent liquid is sucked through the fabric of the clothing, until a point is 55 reached at which such water sucked into head 10 nullifies the vacuum of the latter.

At this point, the clothing C is released by ports 27 and 30 and floats loosely in the water. Considerable water turbulence, effective in washing, is physically occasioned 60 by head 10 in its upward stroke, which is preferably completed when the ports 30 are still approximately an inch below the surface of the water, so that captive water is retained in head 10. Should the ports be above the water line, such captive water is released and replaced by outside 65 air, which calls for the renewal of the priming air purging and liquid priming of the head upon further downward and upward stroke or strokes.

However, assuming that head 10 remains liquid-primed, downward strokes thereof cause the liquid to be discharged under force through ports 27 and 30 and the fabric adjoining the same, with intervening upstrokes producing the reverse or counterflow of the liquid mentioned above.

It is seen that the invention affords a very simple, compact and manually operable clothes washing device for

use on special occasions, when conventional washing means is not available, or its use unjustifiable. The operation is performed readily and in a very brief interval of time, without requiring the application of undue energy; and successive, individually small charges of clothing, amounting in gross to a considerable volume, may be thoroughly and expeditiously cleansed in a relatively small overall period of time.

What I claim as my invention is:

1. A clothes washing device, comprising a hollow bulbous and elastically deformable washer head adapted to have successive axial washing strokes imparted thereto under which the head is elastically deformed, returning toward original form between strokes, a wall of said head having a plurality of openings therethrough for the inflow and outflow of fluid in a generally axial direction as such strokes are imparted, said head wall having externally protuberant annular bead formations surrounding the respective wall openings.

2. A clothes washing device, comprising a hollow bulbous and elastically deformable washer head adapted to have successive axial washing strokes imparted thereto under which the head is elastically deformed, returning toward original form between strokes, a wall of said head having a plurality of openings therethrough for the inflow and outflow of fluid in a generally axial direction as such strokes are imparted, and further openings whose outline extends at least in part into the side of the head for a more lateral fluid outflow and inflow, said head wall having externally protuberant annular bead formations surrounding the respective first named wall openings.

3. A clothes washing device, comprising a hollow bulbous and elastically deformable washer head adapted to have successive axial washing strokes imparted thereto under which the head is elastically deformed, returning toward original form between strokes, a wall of said head having a plurality of openings therethrough for the inflow and outflow of fluid in a generally axial direction as such strokes are imparted, and further openings whose outline extends at least in part into the side of the head for a more lateral fluid outflow and inflow, said head wall having externally protuberant annular bead formations surrounding the respective first named wall openings and said further openings being free of such bead formations.

4. A clothes washing device, comprising a hollow bulbous and elastically deformable washer head adapted to have successive axial washing strokes imparted thereto under which the head is elastically deformed, returning toward original form between strokes, a wall of said head having a plurality of openings therethrough for the inflow and outflow of fluid in a generally axial direction as such strokes are imparted, and further openings whose outline extends at least in part into the side of the head for a more lateral fluid outflow and inflow, said head wall having externally protuberant annular bead formations surrounding the respective first named wall openings and said further openings being free of such bead formations, the remainder of said head being substantially imperforate.

5. A clothes washing device, comprising a hollow bulbous and elastically deformable washer head having means for imparting successive axial washing strokes thereto under which the head is elastically deformed,

returning toward original form between strokes, a wall of said head remote from said stroke imparting means having a plurality of openings therethrough for the inflow and outflow of fluid in a generally axial direction as such strokes are imparted, and further openings whose outline extends at least in part into the side of the head for a more lateral fluid outflow and inflow, said head wall having externally protuberant annular bead formations surrounding the respective first named wall openings and said further openings being free of such bead formations, the remainder of said head adjoining said stroke imparting means being substantially imperforate.

6. A clothes washing device, comprising a hollow bulbous and elastically deformable washer head having means for imparting successive axial washing strokes thereto under which the head is elastically deformed, returning toward original form between strokes, an upper wall of said head being of conical cross-section connecting downwardly to another wall of said head remote from said stroke imparting means having a plurality of openings therethrough for the inflow and outflow of fluid in a generally axial direction as such strokes are imparted, said other wall being of substantial extent in a direction generally paralleling that of said strokes, said wall of conical cross-section being reinforced by an internal formation to afford additional resistance to elastic deformation.

7. A device in accordance with claim 6, in which said head has an annular outwardly projecting flange facing from said upper head wall in the direction axially away from said stroke imparting means.

8. A device in accordance with claim 5, in which said washer head is formed adjacent said stroke imparting means in a generally conical wall formation tapering toward said means, which formation is reinforced to afford additional resistance to elastic deformation.

9. A device in accordance with claim 5, in which said washer head is formed adjacent said stroke imparting means in a generally conical wall formation tapering toward said means, which formation is reinforced to afford additional resistance to elastic deformation, said head having an annular outwardly projecting flange facing from said wall formation in the direction axially away from said stroke imparting means.

10. A device in accordance with claim 4, in which said head wall is thickened in a zone between said imperforate remainder thereof and said further openings to control the action of said washer head in its elastic deformation.
